(57) **CLAIM**

The ornamental design for an indoor cultivation apparatus, as shown and described.

DESCRIPTION

1. Indoor cultivation apparatus
  - 1.1—Front
  - 1.2—Back
  - 1.3—Left
  - 1.4—Top
  - 1.5—Bottom
  - 1.6—Top view of the growing surface taken horizontally at the center of the lamp leg
  - 1.7—Top view of the lamp isolated from the growing surface
  - 1.8—Bottom view of the lamp taken horizontally at the center of the lamp leg
  - 1.9—Perspective
- The right side view is omitted because it is a mirror image of the left side view.
The change to the specification deletes a duplicate set of descriptions.
